REFRACTORY REGENERATOR BRICK

James E. MacDonald, Pittsburgh, Pa.

Application April 24, 1933, Serial No. 667,671

1 Claim. (Cl. 263—51)

My invention is a refractory regenerator brick and is especially suitable for open hearth furnaces, heating furnaces, soaking pits and blast furnace stoves, although it is susceptible of use in various other ways.

Regenerators commonly referred to as checkers constitute a major portion of most furnaces and their purpose is to absorb heat from the waste gases on way to the stack, and to give off this absorbed heat, when furnace is reversed and operating in the opposite direction.

The primary consideration is the size of flue openings and heating surface of the brick used to construct the checkers, of which there are many conditions and as many styles of brick and methods of laying. It has long been desirable to get a checker with proper flue openings with a maximum of heating surface from the brick used.

Most checkers have some offsets or shelves, which tend to accumulate dirt, slag and other deposits from the outgoing waste gases and products of combustion. This accumulation of deposits prevents the brick from absorbing the desired heat, thus greatly lowering the efficiency of the checkers.

One object of my invention is to provide a checker with a maximum of exposed surface of the brick, with a minimum of material. This is accomplished by the small loss of heating surface, in brick to brick joints.

Another object of my invention is to provide a checker with flues so arranged, to permit air and gases to travel vertically, horizontally and diagonally.

Another object of my invention is to provide a brick with all rounded surfaces, when laid up in working order. The all rounded surfaces reducing friction of the air and gases passing through the regenerator to a minimum, and leaving no shelves or flat surfaces to accumulate dirt, slag and other deposits.

Another object of my invention is to provide a generally simplified and improved checker, my bricks are merely stacked in successive tiers, one against another, forming a checker structure having circular flue openings.

Another object of my invention is to provide stronger checker-work, as the arms of my bricks, which extend across flues forming the openings, support no weight from above, as the weight is carried down through the center of the tiers, thus the arms are not affected by heat under load.

Another object of my invention is to avoid what may be termed crowding or cramping of the gases, such as occurs when horizontal flue

openings are few or entirely absent. The lateral flue openings in my design permits the expansion of the air and gases within the checker-work.

Another object of my invention is to provide a brick forming a checker structure so designed for increasing or decreasing the size of the checker flue openings, to give regulated control and distribution of the furnace gases in the checker chambers. For example; using my checker bricks it is possible to make larger or smaller flues at designated sections in the checker-work. This is acquired by using one size or shape brick in building the structure, and altering only the radius on the arms.

Fig. 1 is a plan view of my regenerator brick. 70
Fig. 2 is a side elevation of Fig. 1.

Fig. 3 represents a plan view of my brick with a slight variation in the size of the arms, to show how this brick may be changed to give desired flue openings, without getting away from my 75 original design.

Fig. 4 is a side elevation of Fig. 3.

Fig. 5 represents a section of a side elevation of the regenerator chamber of an open hearth furnace, with my bricks assembled in typical 80 style. Fig. 6 is a view, on an enlarged scale, taken on the line VI—VI of Fig. 5. The numeral 3 represents flue openings or passages through which the waste gases travel on way to the stack. The brick absorbing the heat from these gases 85 for the purpose of heating the incoming cold air, when furnace is reversed and operating in the opposite direction.

The numeral 4 indicates checker support tile, comprising part of the under-structure of the 90 checker-work, and provides the proper spacing for the laying of the checker bricks.

The numeral 5 represents checker rider-walls, and as the name implies, provides the main under-structure for the checker-work and room 95 for the accumulation of dirt, slag and other deposits, carried down through the checkers.

The numeral 6 represents the bridgewall, which separates the slag pockets from the checker-work, for the purpose of preventing slag from 100 getting into the regenerator chamber.

The numeral 7 represents the regenerator chamber roof.

The numeral 8 indicates the port down-takes, 105 through which the outgoing gases travel after leaving the furnace body and ports, on its way to the regenerator chambers and finally out to the stack.

The numeral 9 indicates the slag pocket, so 110

placed to collect the heavy slag deposits carried down through the furnace ports.

The numeral 10 indicates path or course of the furnace gases, traveling through the port down-takes, over the bridgewall into the checkers proper.

The numeral 11 represents regenerator chamber sidewall.

The projections at the six sides of the bricks 10 as shown in Figs. 1 and 2 are of circular form in cross-section, and gradually increase in diameter, so that arcs are formed which extend from the outermost end of each projection to the outermost ends of the adjacent projections. When 15 the bricks are assembled as shown in Figs. 5 and 6, circular passageways are formed thereby for the flow of gases.

The projections at the sides of the bricks are provided with knobs 1 and recesses 2 which can

be interlocked with one another, as shown in Fig. 6, thus facilitating assembly of the bricks, and also rendering them less liable to displacement.

I claim as my invention:—

A checker structure for furnaces, comprising bricks each having six projecting sides which are of circular form in cross section and are of such gradually-increasing diameter from their outermost surfaces to their base portions that they are concave along lines extending from said outermost surfaces to the said base portions, the bases of adjacent projections merging with one another to form arcs which extend from the extremity of one projection to the extremities of adjacent projections, and the said projecting sides of each brick abutting against the similarly formed sides of adjacent bricks.

JAMES E. MACDONALD.
